Inventor:
Theodore Wolf
By Jno. G. Elliott Atty.

UNITED STATES PATENT OFFICE.

THEODORE WOLF, OF CHICAGO, ILLINOIS.

GARMENT-SUPPORTER.

Specification of Letters Patent.

Patented Dec. 15, 1914.

1,120,990.

Application filed January 31, 1910. Serial No. 540,972.

To all whom it may concern:

Be it known that I, THEODORE WOLF, a citizen of the United States, and a resident of Chicago, in the county of Cook and State of Illinois, have invented certain new and useful Improvements in Garment-Supporters, of which the following is a full, clear, and exact specification.

This invention relates to improvements in garment supporters in which one article of wearing apparel is secured to a safety pin, in turn suspended by a plate from another article, as for example in the suspending of skirts and hosiery.

The prime object of my invention is a means by which the spring pin of a safety pin, such as is ordinarily employed by skirt holders, may not only be relieved entirely from the weight of the garment supported, but the safety pin structure, as a whole, be stiffened throughout against lateral strains tending to bend either of its wire members.

In other words, the object of my invention, broadly stated, is to utilize a safety pin in a garment holder as a means of securing a skirt or hosiery thereto, and at the same time transfer its weight from the safety pin to the plate suspended from the waist band.

More specifically stated the object of my invention is a garment supporter comprising a hook plate and a safety pin secured thereto, provided with a latch piece hinged to the hook plate and embracing the spring member of the safety pin in such a manner that the weight of the garment is through said latch piece directly suspended from the hook plate, and both members of the safety pin are prevented from bending.

With these ends in view, my invention finds embodiment in certain features of novelty in the construction, combination and arrangement of parts by which the said objects and certain other objects hereinafter appearing are attained, all as fully described with reference to the accompanying drawings, and more particularly pointed out in the claims.

In said drawings: Figure 1 diagrammatically shows a garment supporter containing my invention in its operative position upon the wearer when used for suspending a skirt. Fig. 2 is a rear elevation of my garment supporter as it appears when substantially of full size. Fig. 3 is a front eleva-

tion thereof; and, Fig. 4 is a transverse section on the line 4—4 of Fig. 2.

Similar characters of reference indicate the same parts in the several figures of the drawings.

5 indicates a flat plate provided with a hook 6 adapted to embrace a waist band 7, or by means of elongated slots 8—8 to be threaded on a belt, the lower end of the plate 5 is provided with an eye 9, preferably bent therefrom and adapted to receive and hinge the fixed bar 10 of an ordinary safety pin, which bar is preferably bent downwardly as indicated at 11 on each end of the eye to prevent its longitudinal movement therein.

The safety pin is of the ordinary construction, that is to say, is provided with a catch 12 secured to one end of the bar 10 and adapted to receive the point of the 75 spring pin 13, the shank of which terminates in a coil 14 integral therewith and with the bar 10, and partly inclosed by a shield 15 preventing the coil from spreading or catching in the garment.

Toward its lower extremity the hook plate 5 is provided with a pair of slots 16 and 17 respectively, the metal separating the slots forming a pivot bearing for eyes 18 and 19 formed on the base of a latch 20, which 85 terminates in a hook 21 adapted to embrace the pin member 13 of the safety pin, thereby connecting the same with the hook plate, with the result that a skirt or other garment upon the pin member is prevented 90 from bending the pin either by its weight or by a pull thereon, the weight of the garment being transferred entirely from the pin to said hook plate.

It will be observed that the latch 20 is so arranged and hinged that it will hook over and embrace the pin about midway its length, the advantage of which is that by passing the pin through two folds of the garment so that the latch lies between those 100 two folds, the garment is balanced on the pin, and in no event, whether the pin is secured to one fold or two folds can the movement of such garment, as for instance a skirt on the pin, be more than half the length of 105 the pin. By thus limiting the possible movement of the garment to half the length of the pin there must be a more than ordinary hard pull thereon or the garment, such for instance as a skirt, must be excessively 110

heavy, before it is possible for the fixed bar of the pin to slide through the eye 11 so that the pin may hang endwise with reference to the plate to the disarrangement and adjustment of the garment.

As a means for maintaining the latch out of its operative position, when securing the safety pin in the garment and its catch, the latch piece is provided with a lug 22 engaging a spring 23 which, as shown, is struck up from the plate, which lug and spring also serve to prevent the movement of the latch piece away from the frame member of the safety pin when in engagement therewith by means of its hood 21.

While the embodiment of my invention herein shown and described is very practical, my invention is not limited to its specific details, as for example, the employment 20 of slots or hooks for the attachment to and suspension of the garment supporter from a waist band, for any other common well known attachment devices may be used for this purpose, and instead of forming the 25 latch from sheet metal it may be formed from wire, and in either instance be hinged to the fixed bar of the safety pin instead of to the plate as shown, and it will be no departure from my invention to substitute a 30 coiled spring for the tongue spring, either stamped from or separately secured to the plate for sustaining the latch out of its operative position until the spring pin of the safety pin is secured in its operative 35 position in and to the garment and in its locked position with its point projecting into the catch 12.

Having described my invention, what I 40 claim and desire to secure by Letters Patent is:—

1. A garment supporter comprising in combination a suspending plate, a safety pin hinged thereto, a latch hinged to said plate

and adapted to engage and prevent the pin member of the safety pin from moving out 45 of its operative position, and a spring upon said plate adapted either to maintain said latch out of its operative position or to sustain it from accidental detachment from the pin member when in its operative position, 50 substantially as described.

2. A garment supporter comprising in combination a suspending plate, a spring and pivot bearing stamped out of said plate, a safety pin flexibly connected with said 55 plate, and a latch embracing said pivot bearings and adapted to engage the pin member of the safety pin and provided with a lug actuated by said spring when the latch is out of its operative position, and whereby 60 the latch is held against accidental movement when in its operative position upon the pin member, substantially as described.

3. A garment supporter comprising in combination a plate provided with belt slots 65 therein, and a hook at one end of the plate, a safety pin suspended from the opposite end of said plate, a latch pivoted to the plate adjacent the last named end, and provided with a hook adapted to embrace and maintain the spring member of the pin in its catch, a spring formed in said plate and a lug on the latch adapted to be engaged by the spring either to maintain the latch out of its operative position or to sustain it 75 against disengagement from the pin member when in its operative position, substantially as described.

In witness whereof, I have hereunto set my hand and affixed my seal, this 28 day 80 of January, A. D. 1910.

THEODORE WOLF. [L.S.]
